UNITED STATES PATENT OFFICE.

PETER MAYHEW LIBBY, OF WATERVILLE, MAINE, ASSIGNOR OF ONE-HALF
TO WILLIAM H. K. ABBOTT, OF SAME PLACE.

YARN-CONTROLLER FOR SPINNING-MACHINES.

SPECIFICATION forming part of Letters Patent No. 665,237, dated January 1, 1901.

Application filed July 7, 1898. Serial No. 685,358. (No model.)

To all whom it may concern:

Be it known that I, PETER MAYHEW LIBBY, of Waterville, in the county of Kennebec and State of Maine, have invented a new and Improved Vibration-Regulator, of which the following is a full, clear, and exact description.

My invention relates to ring - spinning frames; and its object is to provide a new and improved vibration-regulator which is simple and durable in construction and arranged to overcome the irregular ballooning and tension heretofore given to the yarn or thread by the oscillation of the ring-rail and to insure an even tension at all points of winding the yarn or thread on the bobbin.

In spinning and winding thread on bobbins by means of ring-spinning machines the ballooning of the thread is subject to irregularities as the winding progresses. This feature of these machines is very objectionable, since the tension of the feed-rollers is maintained constant throughout the length of the bobbin, and the irregular ballooning causes the thread to break. These irregularities are due to two distinct causes—first, the decrease of the distance between the thread-eyes and the traveler as the ring-rail is lifted by successive stages to compensate for the piling up of the thread on the bobbin; secondly, the variation of the distance between the thread-eyes and the traveler caused by the oscillation of the ring-rail in winding from the large diameter to the small and reversely and the difference in tension caused by so winding.

To provide means for obviating the first irregularity has been the object of many inventions patented both in this country and abroad. Among the devices so designed are several for raising or tilting the thread-board during the winding of the upper portion of the bobbin, where the difficulty is greatest. In all of these devices the thread-board is raised intermittently and left in its elevated position until the bobbin is completed. It has no downward movement during the winding.

The second irregularity noted above has, so far as I know, never been noticed, or at least no attempt has ever been made to

remedy it. It is an improvement of this character which forms the subject-matter of this application for patent, and I explicitly disclaim any intention of endeavoring to claim any device of the first kind. To be sure, such a device might be used to advantage in combination with mine; but there would be no necessary combination between the two. In my regulator the thread-board is oscillated in unison with the ring-rail. It is returned to its initial position after each oscillation, and is therefore not intermittently raised and left in its elevated position until the bobbin has been completed.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement with parts broken out. Fig. 2 is a sectional side elevation of the same on the line 2 2 in Fig. 1. Fig. 3 is a similar view of the same with parts in a different position. Fig. 4 is a cross-section of part of the improvement on the line 4 4 in Fig. 2, and Fig. 5 is a sectional plan view of another part of the improvement on the line 5 5 in Fig. 3.

The ring-spinning frame is provided with the tension-boards A A', hinged at their inner ends to the rails B B', respectively, of the frame of the machine, the outer ends of the boards carrying the usual eyes C C', respectively, for the threads or yarns D D' to pass through to the corresponding bobbins E E'. The thread-boards A A' normally rest in a horizontal position on friction-rollers F F', journaled in the free ends of arms G G', respectively, of which the arm G is secured on a shaft H, journaled in suitable bearings carried by brackets B², attached to the rail B. The other arm G' is mounted to swing loosely on a shaft H', journaled in a bearing carried by a bracket B³, secured to the other rail B'. The arm G has an extension G², in which is held vertically adjustable a stud G³, engag-

ing an elongated horizontally-extending slot G⁴, formed in an extension G⁵ of the arm G', so that when a swinging motion is given to the arm G then the extension G², by the stud 5 G³, imparts a like swinging motion to the extension G⁵ and the arm G'.

In order to impart a swinging motion to the arm G, I fasten on the shaft H a downwardly-extending arm I, supporting a stud I', held 10 vertically adjustable in a slot I², formed in the arm, and said stud is pivotally connected by a link I³ with a stud I⁴, extending through an elongated slot I⁵ in the said link, said stud being carried by an arm I⁶, secured on the 15 shaft H' and parallel to the arm I.

On the shaft H' is secured a lever-arm J, pivotally connected at its free end with a reciprocating rod K, connected with the usual builder-arm of the ring-spinning machine, so 20 that when the latter is in motion an up-and-down movement is given to the rod K to impart a like swinging motion to the lever-arm J. When the latter is thus moved, a rocking motion is given to the shaft H', and its 25 motion is transmitted by the arm I⁶, link I³, and arm I to the shaft H to impart a swinging motion to the arm G, and as the latter is connected with the arm G', as above described, a like movement is given to said arm 30 G'. When the arms G G' swing upward, their friction-rollers impart an upward-swinging motion to the thread-boards A A', so that the thread guides or eyes C C' are raised to the desired position and distance by the upward movement of the ring-rail and the threads thereby relieved of the extra tension given to them when being wound upon the smallest diameter of the bobbin. When the arms G G' swing downward, then the thread- 40 boards A A' by their own weight follow the downward movement of the said arms, so as to govern and control the vibration of the threads or yarns in the same manner as during the upward movement—that is, according 45 to the proportion of the yarns or threads wound on the bobbins E and E'. When the yarn or thread is winding on the largest diameter of the bobbin, it balloons very much more than when it is winding on the smallest 50 diameter of the bobbin, or when winding from the largest diameter to the smallest on the bobbin, as hereinbefore set forth, then the tension increases. Thus by the arrangement described the irregular tension given to the 55 yarns or threads by the oscillation is completely avoided and an even tension is given to the yarns or threads at all points of winding on the bobbin. By having the link I³ adjustable with the stud I' on the arm I and 60 adjustable on the stud I⁴ any desired throw can be given to the thread-boards A A' by the same movement of the reciprocating rod K. When the bobbins are full, the machine is 65 stopped and the full bobbins are replaced by empty ones, and in order to permit the change mentioned it is necessary that the thread-

boards A A' be lifted or swung upward to a point above their uppermost position when the machine is in operation. In order to do this, the lever-arm J is provided at its free 70 end with an angular elongated slot J', into which extends a stud K' on the rod K, said stud being normally locked in place in the upper end of the slot J' by the hook end L' of a latch L, fulcrumed at L² on the arm J, 75 the latch having a second hook L³, adapted to engage a keeper N, secured on the rail B. Thus when the operator swings the latch L upward into the position shown in Fig. 3 and locks the latch to the keeper N then the stud 80 K' is free to slide in the angular slot J' and the arm J can be swung up a considerable distance to impart an upward swinging motion to the thread-boards A A' above their highest position when the machine is in operation. The lever-arm J, previously mentioned, is weighted, as at J², for counterbalancing purposes to insure an easy movement of the various parts.

Having thus fully described my invention, 90 I claim as new and desire to secure by Letters Patent—

1. In a ring-spinning frame, the combination, with pivoted thread-boards, of shafts connected together to rock in unison, an arm 95 on each shaft, said arms having their inner ends connected together by a pin and slot and their outer ends projecting under the thread-boards and provided with friction-rollers upon which said boards rest, a lever-arm secured to one shaft, and means for imparting a swinging motion to the lever-arm, substantially as described. 100

2. In a ring-spinning frame, the combination with pivoted thread-boards, of shafts 105 having depending arms adjustably connected with each other, a second arm on each shaft, said second arms having their inner ends connected by a pin and slot with each other and their outer free ends projecting under the 110 thread-boards, and upon which the thread-boards rest, a lever-arm secured to one shaft and means for imparting a swinging motion to said lever-arm, substantially as described. 115

3. In a ring-spinning frame, the combination with pivoted thread-boards, of shafts 115 each provided with a depending arm, one of which is slotted, a link having one end slotted and connected with one of the said arms and its other end connected with the slotted 120 arm, an arm on each shaft, said arms having their inner ends connected with each other by a pin and slot, and their outer ends engaging the under side of the thread-boards, and a counterbalanced lever-arm secured to 125 one shaft and means for imparting a swinging motion to the lever-arm, substantially as described.

4. A ring-spinning frame, provided with pivoted thread-boards, arms mounted to swing 130 and connected with each other to move in unison, the free ends of the arms engaging

the thread-boards to impart an upward swinging motion to the same, the thread-boards following the free ends on the receding of the same, a lever-arm, means for imparting a swinging motion to the lever-arm, an adjustable connection between the said lever-arm and one of the thread-board arms, and a latch

on said lever-arm for locking and unlocking the connection of the machine with and from said lever-arm, as set forth.
